(57) **CLAIM**

The ornamental design for crystal crayon, as shown and described.

DESCRIPTION

FIG. 1 is a front elevational view of the first embodiment of the crystal crayon showing our design;

FIG. 2 is a rear elevational view of the first embodiment;

FIG. 3 is a top plan view of the first embodiment;

FIG. 4 is a bottom plan view of the first embodiment;

FIG. 5 is a right side elevational view of the first embodiment;

FIG. 6 is a left side elevational view of the first embodiment;

FIG. 7 is a perspective view of the first embodiment;

FIG. 8 is a front elevational view of the second embodiment;

FIG. 9 is a rear elevational view of the second embodiment;

FIG. 10 is a top plan view of the second embodiment;

FIG. 11 is a bottom plan view of the second embodiment;

FIG. 12 is a right side elevational view of the second embodiment;

FIG. 13 is a left side elevational view of the second embodiment; and,

FIG. 14 is a perspective view of the second embodiment.
